DESIGN FOR A PANEL FOR AN AMUSEMENT
DEVICENorman Latimer Roberts, Seventrees, Rotherfield,
EnglandApplication May 9, 1940, Serial No. 92,243
In Great Britain December 18, 1939

Term of patent 14 years

To all whom it may concern:

Be it known that I, Norman Latimer Roberts, a subject of the King of Great Britain, residing at Seventrees, Rotherfield, in the county of Sussex, England, have invented a new, original, and ornamental Design for a Panel for an Amusement Device, of which the following is a specification, reference being had to the accompanying drawing forming part thereof.

The figure is an elevational view of a panel for an amusement device showing my new design.

The article is of no appreciable or substantial thickness and the features of the design are flush with the surface of the panel.

I claim:

The ornamental design for a panel for an amusement device, as shown and described.

NORMAN LATIMER ROBERTS.
